UNITED STATES PATENT OFFICE.

P. W. GATES, OF CHICAGO, ILLINOIS.

IMPROVEMENT IN CASTING STAMPING-HEADS.

Specification forming part of Letters Patent No. 29,372, dated July 31, 1860.

To all whom it may concern:

Be it known that I, PHILETUS W. GATES, of Chicago, in the county of Cook and State of Illinois, have invented a new and Improved Mode of Casting Chilled Stamping Heads and Dies; and I do hereby declare that the following is a full, clear, and exact description of the same, reference being had to the accompanying drawings, forming a part of this specification, in which—

Figure 1 represents a vertical central section of the flask and center piece put together ready for casting the stamp-head; Fig. 2, a similar section through the center piece detached from the flask; Fig. 3, a similar section, and Fig. 4 a plan of the stamp-head when cast onto the center piece; Fig. 5, a vertical central section of the flask and center piece ready for the casting of the die; Fig. 6, a horizontal and Fig. 7 a vertical section of the die when cast onto the center.

Similar letters of reference in each of the several figures indicate corresponding parts.

The nature of my invention consists in the use of a hollow central chill, in combination with an external chilled metal flask, in the manner substantially as hereinafter described, so that the metal which, with the central chill, forms the stamp head or die may be cast in and around the central chill and against the interior surface of the external chilled flask. The object of this process is to chill the metal of the stamp head and die all through, and thus increase their durability. Stamp heads and dies as manufactured at present are chilled to a thickness of from one-quarter to an inch only. When this thickness is worn off the rest is very readily used up.

To enable others skilled in the art to make and use my invention, I will proceed to describe its construction and operation.

I first cast the hollow stem B of the stamp-head, the lower part, B² B³, in an iron flask, and the upper part, B' B'', in a second mold, so as to chill the lower part of the stem, (which is to form part of the head,) and to have the upper part, or what may be properly called the "stem," of the stamp-head soit, so that it can readily be turned. The stem, when finished, is placed in an iron flask, D D', as represented in Fig. 1, so that its chilled lower portion forms a center piece of the hollow

space of the flask. The molten metal is then poured through the hollow stem into the flask so as to fill the hollow space in the flask and stem, as represented at A A' A, Fig. 3. The stem is originally cast with recesses x on its inner and recesses y on its outer surface, which are afterward filled up by the metal A A' A, so that when the bottom part of the stamp-head becomes worn off, and only a ring, A A, is left around and a core, A', in the stem, this ring and core will yet be firmly connected with the stem and fit for use. As the metal is cast through and around the stem, (in the above-described manner,) it is not only chilled from the outside in consequence of its contact with the inner surface of flask D D', but also from the inside in consequence of its contact there with the center piece formed by the lower end of the stem. Thus the metal will be chilled throughout, and will thereby be made far more durable than what the usual stamp-heads are.

I found it necessary to cast the metal through and around a hollow center piece, because on casting it around a solid stem it would invariably crack. On pouring the molten metal through the hollow center piece it heats and expands and can afterward contract together with the cast head so as to prevent its cracking. The die d is cast in a similar manner around and through a ring-like center piece, b, which is fastened in the flask a a' by pins c. The center piece, b, is made of chilled cast-iron and provided with recesses similar to the recesses x y above described. In this manner the die is also chilled throughout from the center as well as from the outside, and is thus made to possess a high degree of durability.

What I claim as my invention, and desire to secure by Letters Patent, is—

The use of a hollow central chill, in combination with an external chilled metal flask, in the manner substantially as and for the purposes herein described.

The above specification of my improved mode of casting chilled stamping-heads, &c., signed by me this 30th day of April, 1860.

P. W. GATES.
